UNITED STATES PATENT OFFICE

168,599

BUILDING BRICK

Byron E. Scott, St. Paul, Minn.

Application February 16, 1952, Serial No. 18,545

Term of patent 14 years

(Cl. D18—2)

To all whom it may concern:

Be it known that I, Byron E. Scott, a citizen of the United States, residing at St. Paul, county of Ramsey, and State of Minnesota, have invented a new, original, and ornamental Design for a Building Brick, of which the following is a specification, reference being had to the accompanying drawing, forming a part hereof.

Figure 1 is a perspective view of a building brick, showing my new design;

Figure 2 is a top plan view of the same.

I claim:

The ornamental design for a building brick, as shown.

BYRON E. SCOTT.
